UNITED STATES PATENT OFFICE.

MAURICE ZUCKER, OF CLEVELAND, OHIO.

GAS-REGULATOR.

SPECIFICATION forming part of Letters Patent No. 355,673, dated January 4, 1887.

Application filed September 16, 1886. Serial No. 213,701. (No model.)

To all whom it may concern:

Be it known that I, MAURICE ZUCKER, a citizen of the United States of America, residing at Cleveland, in the county of Cuyahoga and State of Ohio, have invented certain new and useful Improvements in Gas-Regulators; and I do hereby declare the following to be a full, clear, and exact description of the invention, such as will enable others skilled in the art

10 to which it appertains to make and use the same, reference being had to the accompanying drawings, and to letters or figures of reference marked thereon, which form a part of this specification.

15 My invention relates to certain new and useful improvements in gas-regulators, the object of the same being to provide a means for preventing the noxious odors of the gas escaping from the regulator; and to this end my invention consists in providing the regulator above its diaphragm with a supplemental diaphragm of impervious material, said diaphragms being free from contact with each other, except at the edges; also, in providing a regulator having such an impervious diaphragm with an inwardly-curved flange, as will be hereinafter fully set forth, and specifically pointed out in the claims.

20 In the accompanying drawings I have shown my invention applied to a gas-regulator of ordinary construction, such a gas-regulator being shown in Figure 1 of the drawings. Fig. 2 of the drawings is a sectional view taken through the line *x x* of Fig. 1, illustrating fully the application of my improvements.

25 A refers to the casing of a gas-regulator, which is preferably made of cast metal, *a* being a coupling, to which the gas-supply pipe is attached. The casing of the regulator above the supply-coupling is provided with a valve-seat, *b*, under which the valve *B* will operate, so as to cut off or increase the supply-opening, which valve is operated automatically by pressure of the gas.

30 C refers to the discharge-opening, through which the gas passes to the burners. The body portion of the regulator is preferably made in two parts, which are secured to each other by bolts *c*, the upper portion of the regulator having an opening therein, so that access can be had to the valve-stem for attaching weights

thereto. The engaging parts of this opening and cap may be threaded; or the opening may be provided at opposite sides with vertical grooves, to admit of the passage of projection 55 *d* on the lower rim of the cap-flange; or the parts may be arranged in any other usual or preferred manner, so long as the cap is adapted to be secured over the opening and to be removed, if necessary.

40 In practice it has been found that the removable cover *D*, at the point where it is attached to the casing, is liable to leakage, and that the gas, after the regulator has been in use for some time, will pass through the diaphragm *E* 65 and escape through the opening in the upper portion of the regulator. To obviate this objection, I attach above the diaphragm *E* a supplemental diaphragm, *F*, which is centrally secured to the valve-stem *e* at a distance above 70 the point of attachment of diaphragm *E* in any suitable manner, so as to form a tight joint, nuts located one above the other, between which the diaphragm is secured, being a preferred form of securing the parts to each other. 75 The diaphragm *F* is preferably made of impervious material—such as rubber, cloth, or other textile fabric—through which the gas cannot pass, and which will remain at all times pliable.

45 Immediately above the diaphragm *E* is secured a circular metal flange having a central opening and inwardly-curved edges, as shown at *G*, thus providing a curved ring or collar, against which the diaphragm *F* will contact and find support when distended by pressure of gas, as shown by dotted lines in Fig. 2. Without such a supporting ring the upper diaphragm would be liable to break or leak, especially after long use and when the diaphragm 90 becomes saturated with the impurities contained in the gas.

50 By means of my improvement gas-regulators can be constructed so that there will be absolutely no leakage, and what gas may leak 95 through the first diaphragm will be caught and held by the supplemental diaphragm, and as soon as the pressure is reduced will flow back through the diaphragm *E* to the exit-opening of the regulator.

I claim—

55 1. In a gas-regulator, the combination, with

- the casing, the valve-stem, and the main diaphragm secured at its edges to the casing and at its center to the stem, of a supplemental diaphragm having its edges secured upon the edges of the main diaphragm, and at the center connected adjustably to the valve-stem at a distance above the main diaphragm by independent connecting devices, substantially as described.
- 10 2. In combination with a gas-regulator having inlet-supply openings, a valve attached to a diaphragm, E, and supplemental diaphragm F, secured above the same, and a flange

or collar, G, located above the supplemental diaphragm, and provided with an inwardly curved rim to support said supplemental diaphragm when distended by gas-pressure, substantially as shown, and for the purpose set forth.

In testimony whereof I affix my signature in presence of two witnesses.

MAURICE ZUCKER.
